DOOR HANDLE

Gilbert J. Haan, Jr., Grand Rapids, Mich., assignor to Keeler Brass Company, Grand Rapids, Mich.

Application February 27, 1936, Serial No. 66,019

12 Claims. (Cl. 292—347)

The main objects of this invention are:

First, to provide a door handle for automobiles which is without projection at the shank or spindle end thereof and therefore not only lends itself to the stream-lined design of the present day automobile but does not have any projecting parts likely to engage persons or objects to cause injury or accident.

Second, to provide a handle having these advantages which is attractive in appearance.

Third, to provide an improved handle structure which is very strong and rigid and at the same time made mainly of sheet metal parts and one which is very economical in structure.

Objects relating to details and economies of the invention will appear from the description to follow. The invention is defined and pointed out in the claims.

Preferred embodiments of the invention are illustrated in the accompanying drawings, in which:

Fig. 1 is a side elevation of my door handle associated with its escutcheon.

Fig. 2 is a fragmentary view mainly in longitudinal section on line 2—2 of Fig. 3.

Fig. 3 is an elevation with the outer casing removed and parts broken away and sectioned on line 3—3 of Fig. 4.

Fig. 4 is a transverse section on line 4—4 of Figs. 2 and 3.

Fig. 5 is a view with the parts mainly in disassembled form or relation.

Fig. 6 is an inside view of a modified embodiment of my invention, the spindle being shown in section.

Fig. 7 is an enlarged fragmentary view mainly in section on line 7—7 of Fig. 6.

Fig. 8 is an enlarged transverse section on line 8—8 of Fig. 6.

Fig. 9 is a longitudinal section of a modified form of back in which the two back members as shown in the other figures are formed as one stamping.

In the embodiments of my invention illustrated, the spindle 1 is bent at its outer end to provide the laterally disposed curved arm 2 which is of substantial length. I provide a shell-like body member 3 of channel cross section and longitudinally curved and preferably tapered to provide the desired taper or shape to the handle.

This body member is formed as a sheet metal stamping and has inwardly offset struck opposed insets 4, 4 and 5, 5 in its side walls, these inset portions abutting against and being spot-welded to the sides of the arm of the spindle as best

shown in Figs. 3 and 4. At each of these insets, portions 7 are left at the bottom of the recesses formed by the insets, the outer surfaces of these portions 7 being flush with the sides of the body member to form continuous supports for the thin shell or casing 8 which is conformed to fit closely the outline of this body member, the shell or casing being made of material that can be suitably finished while the body member may be unfinished or formed as a plain or rough sheet metal stamping.

The ornamental and stiffening rib 9 is preferably provided in the body member and a nesting rib 10 is preferably provided in the casing. The back member 11 is formed with inwardly offset flanges 12 on its edges. This back member is also curved.

A complementary base member 13 is provided, this base member being cup-shaped and having a spherically curved end 14 adapted to fit and rotate within the opening 15 of the escutcheon 16. This base member has laterally turned flanges 17 on its side and rear edges abutting against the edge of the body member. The members 11 and 13 have inturned abutting flanges 18 and 19 respectively on their abutting edges. The casing or shell 8 has inturned flanges 20 in clamping engagement with the inset flanges of the back members 11 and 13.

The escutcheon is suitably shaped to provide a housing for the thrust washers 21 arranged between the spring housing 22 and the swiveling or bearing portion of the base member 13, the spring 23 in the housing 22 acting to prevent rattling and to yieldingly hold the handle in the socket provided therefor by the escutcheon.

With this arrangement of parts, I provide a handle in which there are no projecting parts at the shank or spindle end of the handle and the handle lies close to the door which is particularly desirable where streamlining effects or designs are desired; at the same time the structure is strong and rigid and economical in its parts and very attractive in appearance.

In Fig. 9, the back portion 25 is formed integrally therewith. This back member is designed to be assembled with the spindle, body member, and casing in the same manner as in the embodiment shown in Figs. 1 to 5 inclusive and, therefore, an assembled handle with this back member is not illustrated.

In the embodiment of my invention shown in Figs. 6, 7, and 8, the back member 11 is omitted entirely, a base member 26 corresponding to the base member 13 being provided. The casing 27

is provided with bottom portions 28 which are folded below the arm on the spindle, these portions 28 in themselves constituting a back, the edges of the portions being brought together in 5 abutting relation at 29. Other than the omission of the back member, the structure is, as stated, substantially that of Figs. 1 to 5.

The handle of all these embodiments is without base or shank projections or prongs. At the same time it is attractive in appearance and is 10 of strong and rigid construction even though made mainly of sheet metal.

I have not attempted to illustrate all of the 15 embodiments and modifications which I contemplate as it is believed that this disclosure will enable those skilled in the art to embody or adapt my improvements as may be desired.

Having thus described my invention, what I 20 claim as new and desire to secure by Letters Patent, is:

1. A handle structure comprising a spindle bent at its outer end to provide a laterally disposed curved arm of substantial length, a curved body member of channel cross section receiving said 25 arm and having spaced pairs of opposed insets in the sides thereof welded to the sides of said arm on said spindle, there being portions of said body member at the inner sides of said insets flush with the sides of said body member, a curved back 30 member of channel cross section having offset edge flanges, a cupped base member having a spherically curved escutcheon engaging end arranged on said spindle and complementing said back member and having out-turned flanges 35 abutting the end edges of said body member, said back member and base member having inturned abutting flanges at their meeting edges, and a casing closely embracing said body member and the edges of said back member and base member 40 and having its edges folded inwardly in clamping engagement upon the edge flanges thereof.

2. A handle structure comprising a spindle bent at its outer end to provide a laterally disposed curved arm of substantial length, a curved body member of channel cross section receiving said 45 arm and having insets in the sides thereof welded to the sides of said arm on said spindle, a curved back member of channel cross section having offset edge flanges, a cupped base member having a spherically curved escutcheon engaging end arranged on said spindle and complementing said back member and having out-turned flanges abutting the end edges of said 50 body member, said back member and base member having inturned abutting flanges at their meeting edges, and a casing closely embracing said body member and the edges of said back member and base member and having its edges folded inwardly in clamping engagement upon the edge flanges thereof.

3. A handle structure comprising a spindle bent at its outer end to provide a laterally disposed curved arm of substantial length, a curved body member of channel cross section receiving said 55 arm and having spaced pairs of opposed insets in the sides thereof welded to the sides of said arm on said spindle, there being portions of said body member at the inner sides of said insets flush with the sides of said body member, a curved back member of channel cross section, a cupped base member having a spherically curved escutcheon engaging end arranged on said spindle and complementing said back member, and a casing 60 embracing said body member and clamped upon the edges of said back and base members.

4. A handle structure comprising a spindle bent at its outer end to provide a laterally disposed curved arm of substantial length, a curved body member of channel cross section receiving said arm and having insets in the sides thereof welded to the sides of said arm on said spindle, a curved back member of channel cross section, a cupped base member having a spherically curved escutcheon engaging end arranged on said spindle and complementing said back member, and a casing 10 embracing said body member and clamped upon the edges of said back and base members. 5

5. A handle structure comprising a spindle having an integral laterally disposed arm at its outer end, a body member of channel cross section 15 having insets in the sides thereof welded to the sides of said arm on said spindle, a back member having offset edge flanges, a cupped base member having a curved escutcheon engaging end arranged on said spindle and complementing 20 said back member and abutting the end edges of said body member, and a casing on said body member having its edges folded inwardly in clamping engagement with the edge portions of 25 said back and base members.

6. A handle structure comprising a spindle provided with an arm, a body member of channel cross section having insets in the sides thereof welded to the sides of said arm on said spindle, a back member having offset edge flanges, a cupped base member having a curved escutcheon 30 engaging end arranged on said spindle and complementing said back member and abutting the end edges of said body member, and a casing on said body member having its edges folded inwardly in clamping engagement with the edge portions of 35 said back and base members.

7. A handle structure comprising a spindle bent at its outer end to provide a laterally disposed curved arm, a curved body member of channel 40 cross section having opposed insets at the sides thereof welded to the sides of said arm on said spindle, there being portions of said body member at the inner sides of said insets flush with the sides of said body member, a curved back of 45 channel cross section having edge flanges and provided with a spherically curved escutcheon engaging base portion, and a casing closely embracing said body member and the edges of said back and having its edges folded inwardly in 50 clamping engagement upon the edge flanges thereof.

8. A handle structure comprising a spindle bent at its outer end to provide a laterally disposed curved arm, a curved body member of channel cross section having insets at the sides thereof welded to the sides of said arm on said spindle, a curved back of channel cross section having edge flanges and provided with a spherically curved escutcheon engaging base portion, and a casing closely embracing said body member and the edges of said back and having its edges folded inwardly in 55 clamping engagement upon the edge flanges thereof. 60

9. A handle structure comprising a spindle bent at its outer end to provide a laterally disposed curved arm, a curved body member of channel cross section having insets at the sides thereof welded to the sides of said arm on said 70 spindle, there being portions of said body member at the inner sides of said insets flush with the sides of said body member, a curved back including an escutcheon engaging base portion, and a casing embracing said body member and 75

back and having its edges in clamping engagement with the back.

10. A handle structure comprising a spindle provided with a laterally disposed arm, a body member of channel cross section having insets at the sides thereof welded to the sides of said arm on said spindle, there being portions of said body member at the inner sides of said insets flush with the sides of said body member, a back including an escutcheon engaging base portion, and a casing embracing said body member and back and having its edges in clamping engagement with the back.

11. A handle structure comprising a spindle bent at its outer end to provide a laterally disposed curved arm, a curved body member of channel cross section embracing said arm and welded

to the side thereof, a curved back including an escutcheon engaging base portion, and a casing embracing said body member and back and having its edges in clamping engagement with the back.

12. A handle structure comprising a spindle bent at its outer end to provide a laterally disposed curved arm, a curved body member of channel cross section having insets at the side thereof welded to the sides of said arm on said spindle, there being portions of said body member at the inner sides of said insets flush with the sides of said body member, and a casing embracing said body member and folded around the edges thereof.

GILBERT J. HAAN, JR.
